Primary Examiner — Natasha Vujcic*Assistant Examiner* — Gilbert B Ford(74) *Attorney, Agent, or Firm* — Dorsey & Whitney LLP(57) **CLAIM**

The ornamental design for a urine collection apparatus cover, as shown and described.

DESCRIPTION

FIG. 1 is a front, top, perspective view of a urine collection apparatus cover, according to a new design;

FIG. 2 is a rear, top, perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawings depict portions of a urine collection apparatus and the urine collection apparatus cover that form no part of the claimed design.
